UNITED STATES PATENT OFFICE.

WILLIAM L. DAVIS, OF ROCHESTER, NEW YORK.

THE THERMOSTAT.

1,172,880.

Specification of Letters Patent. Patented Feb. 22, 1916.

Application filed April 17, 1912, Serial No. 691,888. Renewed December 2, 1915. Serial No. 64,774.

To all whom it may concern:

Be it known that I, WILLIAM L. DAVIS, of Rochester, in the county of Monroe and State of New York, have invented a new and useful Improvement in Thermostats, which improvement is fully set forth in the following specification and shown in the accompanying drawings.

The present invention relates to thermostats, and an object of the same is to provide a closed circuit thermostat which is adjustable to operate at different temperatures.

Another object of the invention is to provide a thermostat which may be used upon a closed or an open circuit.

To these and other ends the invention consists in certain parts and combination of parts, all of which will be hereinafter described and the novel features thereof more particularly pointed out in the appended claims.

In the drawings: Figure 1 is a front view of a thermostat constructed in accordance with the present invention; Fig. 2 is a rear view of the same device; Fig. 3 is an axial section through the device before the same has been affected by heat; Fig. 4 is a similar view showing the device after it has been affected by heat; Fig. 5 is a detail view of one of the terminals of another embodiment shown also in Figs. 6 and 7; Fig. 6 is a sectional view of an embodiment employing the terminal shown in Fig. 5, such embodiment being adapted for closed circuits; and Fig. 7 shows the embodiment illustrated in Fig. 6 adjusted for open circuits.

According to the embodiment of the invention illustrated in Figs. 1 to 4, there is employed a cap-shaped member or casing having laterally extending ears 2 or other attaching devices and provided with a central opening 3. Arranged within the casing upon an annular seat 4 is a member 5 formed of a material which readily expands under action of heat, this member, in this instance, being in the form of a rubber disk, which, when arranged upon the seat 4, closes the opening 3 in the casing, but is, by way of such opening, readily affected by changes in temperature. Arranged within

the casing is a terminal 6, preferably in the form of a spring arm secured upon an insulating piece 7 to the inner face of the casing at one side of the disk 5, and extending over and bearing with pressure upon said disk, so that, when the disk expands outwardly under the action of heat, the spring arm follows up said disk. Also arranged within the casing 1 is a terminal 8 which, preferably, rests upon an insulating member 9 and is secured thereto by screws 10, the insulating member 9 being secured by screws 11 to the casing 1 over a portion of the terminal 6 in order to hold the latter in place, lateral or sidewise movement of the terminal 6 being prevented by bending up a lug 12 on the terminal 6 to engage with the insulator 9. The terminal 8 is also in the form of a spring arm extending over the disk 5 and above the terminal 6, having an adjustable contact point 13 in the form of a screw which, when the circuit is closed, bears upon the terminal 6, the arm 8 also having a tendency to follow up and move with the expansible member 5. Conductors 6^a and 8^a may be soldered or otherwise secured to the terminals 6 and 8 respectively and lead thereto from the outside of the casing through openings in the walls of the casings. To the end of separating the terminals 6 and 8, when the desired temperature is reached, there may be employed a separating means in the form of a stop 14 which, preferably, is adjustable, and, to this end, is in the form of a screw operable from the exterior of the casing so as to vary its position with reference to the normal position of the terminal 8 in the path of which it lies. The terminal also may have, on its proximate face, a piece of insulating material 15 which prevents short circuiting of the parts when the terminal engages the stop 14.

The operation of the embodiment shown in Figs. 1 to 4 is as follows: The conductors 6^a and 8^a are connected to their respective terminals and the latter are connected electrically by means of the adjustable contact piece 13, the stop 14 being adjusted so that it lies out of engagement with the extreme 100

end of the terminal 8. With the expansion of the disk member 5, the terminals 6 and 8 move together with said member 5 owing to the fact that they are placed under an initial tension. After they have moved a certain distance, the terminal 8 contacts with the stop 14 and is held against further movement with the member 5, but the terminal 6 continues such movement and breaks the electrical connection between the members 6 and 8. The temperature at which the circuit breaks may be varied by adjusting the position of the stop 14.

The embodiment of the invention shown in Figs. 5, 6 and 7 is designed for obtaining from one device either a closed or an open circuit. The closed circuit is shown in Fig. 6 in which the parts are identical with those shown in Figs. 1 to 4, except that the insulating piece 15^a, corresponding to the insulating piece 15 of Figs. 1 to 4, is movably arranged upon the terminal 8, being preferably pivoted upon the screw 13 and held thereon by a spring washer 16 so as to cover and uncover the under side of the terminal 8. When making a closed circuit thermostat, the parts are assembled as shown in Fig. 6 with the insulator 15^a covering the terminal 8, and the conductors 6^a and 8^a are connected like in Figs. 1 to 4. When making an open circuit thermostat, as shown in Fig. 7, the insulation is shifted to uncover the terminal 8 and the terminal 6 is entirely removed so that the screw 13 bears directly upon the expansible member 5. The conductor 6^a is connected directly to the casing at 6^b.

The operation of the embodiment shown in Figs. 5, 6 and 7 is the same as that shown in Figs. 1 to 4, when this embodiment is constructed as a closed circuit thermostat, but, when constructed as an open circuit thermostat, the stop 14^a acts as a contact point for engagement with the terminal 8 after the movable insulator has been shifted to the position shown at Fig. 5 so that, when the disk 5 expands, the terminal 8 follows up the same until such terminal contacts with the contact point 14^a, thus establishing a circuit from the conductor 8^a to the conductor 6^a which is soldered directly to the casing 1.

From the foregoing it will be seen that I have provided a thermostat for use in closed circuits and having means for adjusting the same to operate at different temperatures. There has also been provided a construction which is adapted to be used with but slight changes as either a closed circuit thermostat or an open circuit thermostat.

What I claim as my invention and desire to secure by Letters Patent is:

1. In a thermostat, the combination with a member adapted to be affected by changes

in temperature, of a pair of terminals moving when the first named member is affected by heat, and an adjustable stop for coöperating with one of said terminals to effect its disconnection with the other terminal.

2. In a thermostat, the combination with a member moving under changes in temperature, of a pair of terminals held with a yielding pressure, one against the other and against the member, and a stop for coöperation with the free end of one of said arms to effect the separation of said terminals upon the moving of the first named member.

3. In a thermostat, the combination with a casing of a disk arranged thereon and bending under changes of temperature, a pair of spring arms acting as terminals, one of said arms bearing against the disk, and the other of said arms bearing against the first named arm, and a stop for coöperation with the last named arm.

4. In a thermostat, the combination with a cup-shaped casing having an opening therein, of a rubber disk arranged to close said opening and to bend under changes in temperature, of a spring arm arranged within the casing, insulated therefrom and bearing with pressure against the inner face of the disk, a second spring arm insulated from the casing and the first named spring arm and having a contact point which under low temperatures bears with pressure against the first named spring arm, and a stop located in the path of the second named terminal to cause the latter to separate from the first named terminal when the rubber disk bends under high temperatures.

5. In a thermostat, the combination with a casing, of a member carried by the casing and adapted to be affected by changes in temperature, a pair of terminals arranged within the casing in electrical connection and movable together under the action of the heat affected member, and an adjustable stop operable from the exterior of the casing and located in the path of one of the terminals to cause the separation of the terminals.

6. In a thermostat, the combination with a casing, of a pair of terminals arranged therein, one of which is detachable, a member affected by changes in temperature and moving both terminals together, a stop for coöperating with one of the terminals to separate them, and an insulator movably mounted on the terminal which coöperates with the stop, said insulator, in one position, insulating the stop from the terminal and, in the other position, permitting electrical connection between them so that the stop may act as a terminal when the detachable terminal is removed.

7. In a thermostat, the combination with a pair of terminals normally electrically connected, one of said terminals being detach-

able, of a device for coöperation with the other terminal to break the electrical connection between them, and an insulator movable to and from a position between the last 5 named terminal and the said device, the said device serving as a terminal when the detachable terminal is removed and the insu-

lator is shifted so that the other terminal may coöperate with the said device.
